UNITED STATES PATENT OFFICE.

RALPH S. CECERO, OF WATERBURY, CONNECTICUT.

TRAIN-STOPPING MECHANISM.

Application filed May 16, 1925. Serial No. 30,858.

This invention relates to train control mechanism and more particularly to a mechanism mounted upon the steam locomotive, for quickly operating rail gripping brake shoes or causing the energization of electromagnets which cooperate with the track rails and produce a magnetic drag, which, with the said rail gripping shoes, result in a sudden stop in movement of the locomotive and train.

It is one of the objects of this invention to provide a rail engaging brake shoe which may be operated by steam pressure generated for propelling the engine, and which 15 brake shoes may be utilized as auxiliary to the drive wheel brakes if so desired, and it is a further object to utilize the steam pressure generated for propelling the engine, for operating a small electric generator for 20 supplying energy to a plurality of electromagnets suitably arranged on the locomotive to cooperate with the rails.

With these and other objects in view, my invention consists in the novel features of 25 construction, combination of arrangement of parts, as will be hereinafter referred to and more particularly pointed out in the specification and claim.

In the drawings,—

Figure 1 is a side elevation of a locomotive illustrating the application of my invention thereto;

Figure 2 is a diagram of the electrical circuit for the electromagnets;

Figure 3 is a side elevation of one of the steam operated rail gripping devices;

Figure 4 is a vertical section on the line 4—4 of Figure 3;

Figure 5 is a view, partly in side elevation and partly in section of the motor generator unit and locomotive steam dome;

Figure 6 is an end elevation of the motor generator unit; and

Figure 7 is a detail side elevation of one 45 of the electromagnets, and illustrating its relation to one of the track rails.

Referring now more particularly to the accompanying drawings by numerals of reference, 1 designates a steam locomotive, adapted to travel upon rails 2, all of which may be of conventional form.

Arranged upon each side of the locomotive, and supported upon the framework thereof, by means of brackets 3, are a pair 55 of steam cylinders 4, within each of which is adapted to reciprocate a piston 5, the rod

6 of which extends through a suitable stuffing box 7 and on its lower end carries a fixed rail engaging brake shoe 8, which, as shown in Figure 4, is provided with a groove 60 9, conforming to the face of the tread of the rail 2, with which it cooperates.

Each of the cylinders, above its piston, is in communication with the steam dome 10 of the locomotive, through pipes 11 and 12, 65 the latter being provided with valves 13 controllable from within the cab 14, through a rod or cable 15.

Operating in conjunction with the steam operated rail gripping brake shoes 8, are a 70 plurality of electromagnets 16, suitably arranged upon each side of the locomotive, and if necessary, the tender 17, and positioned directly above the rails, but slightly spaced therefrom.

The several electromagnets 16 may be of 75 any well known type, each including the winding 18 and core 19, supported by but insulated as at 20, from a hanger bracket 21 secured to the locomotive or tender 80 frame.

The several electromagnets 16 are connected in series in a circuit, including a generator 22, and conductor 23, a switch 24, convenient to the engineer, serving to open 85 or close the circuit as the case may be.

The generator 22 is a part of a motor generator set, the motor being here shown in the form of a steam turbine 25, mounted upon the same base 26 with the generator 90 and being supported upon the locomotive in proximity to the steam dome 10, and the rotors of both generator and turbine being keyed to the same shaft 27. Steam is supplied to the turbine 25 from the steam dome, 95 through a pipe 28, a valve 29 in which is operable from the cab by a rod or cable 30.

Assuming that the locomotive is in motion, and that it is necessary to suddenly bring the locomotive to a stop, it being of course 100 assumed that the brake shoes 8 are retracted and the electromagnets 16, deenergized. Opening of valve 13 in steam pipe 12, permits steam to pass into the several cylinders above the pistons forcing them downwardly 105 into engagement with the rails 2. Simultaneously, the switch 24 in the electromagnet circuit may be closed, and generator 22 being constantly rotated by turbine 25, will cause the electromagnets to be energized, 110 and the latter being in close proximity to the rails, the latter, acting as an armature

- will produce a magnetic drag, and assist the steam operated brake shoes in bringing the locomotive and its train to a stop. It is to be understood that the magnetic and steam operated brakes may be operated independently or provision, such as a unitary control for operating them simultaneously or even successively through a single operating device. It will be observed that no wheel brakes are used upon the locomotive. The arrangement is such that the lifting action of the shoes when applied to the rail is counter-acted by the lowering action of the drag brake at a point between the driving wheels. Therefore, the shoes cannot lift the driving wheels off of the rails and consequently, should the engine be reversed, the driving wheels may also serve as a brake means for the locomotive.
- From the foregoing description of the construction of my improved apparatus, it will be seen that I have provided a simple, inexpensive and efficient means for carrying out the objects of the invention, and while I have particularly described the elements

best adapted to perform the functions set forth, it is obvious that various changes in form, proportion, and in the minor details of construction may be resorted to, without departing from the spirit or sacrificing any of the principles of the invention.

Having described my invention, what I claim as new and desire to protect by Letters Patent is:—

A brake for a rail riding locomotive having a set of driving wheels, comprising a drag brake arranged to operate upon the rail at a point between the driving wheels, and brake shoes adapted to frictionally engage the rail at points beyond the terminal wheels of the set of driving wheels, and means for independently applying the drag brake and the shoes, the arrangement being such that the lifting tendency of the shoes is counter-acted by the lowering tendency of the drag brake when the shoes and the drag brake are simultaneously applied.

In testimony whereof, I affix my signature.

RALPH S. CECERO.
